UNITED STATES PATENT OFFICE.

GEORGE A. ROBINSON, OF BOSTON, MASSACHUSETTS, ASSIGNOR TO PNEUMATIC SCALE CORPORATION LIMITED, OF QUINCY, MASSACHUSETTS, A CORPORATION OF MAINE.

CARTON.

1,007,390.

Specification of Letters Patent. Patented Oct. 31, 1911.

Application filed April 10, 1911. Serial No. 619,921.

To all whom it may concern:

Be it known that I, GEORGE A. ROBINSON, a citizen of the United States, residing at Boston, in the county of Suffolk, State of Massachusetts, have invented a certain new and useful Improvement in Cartons, of which the following is a specification, reference being had therein to the accompanying drawings.

10 The invention relates to that class of cartons in which the top is closed by a plurality of overlapping flaps. Usually four flaps are employed.

15 The object of the invention is to provide a self-opening top as it is frequently termed, so constructed that when closed the contents of the package are securely protected against sifting out and which may be easily manipulated to afford an opening to remove a portion 20 of the contents and which may again be closed to securely protect the material remaining in the package. The carton embodying the invention is preferably made of a single sheet of paper.

25 The invention will be fully understood from the following description taken in connection with the accompanying drawings, and the novel features will be pointed out and clearly defined in the claims at the close 30 of the specification.

In the drawings, Figure 1 is a plan of a blank laid out flat of suitable form ready to be folded to form the carton. Fig. 2 is a top plan of the carton as set up with the top 35 flaps folded and the outlet holes closed by the slide. Fig. 3 is a top plan of the same device as shown in Fig. 2 with the slide drawn out to open the discharge outlet from the carton.

40 Referring now to the drawings:—The carton blank is scored or creased to form the four sides 1, 2, 3, 4, of the carton when the carton is set up, the side 1 being folded around to meet the edge of the side 4, the 45 same being sealed by a flap 5 which laps onto the inner face of the side 1 and is adhesively secured thereto in the ordinary way. The carton may be formed with the bottom closing flaps 6, 7, 8, 9, which may be closed 50 and sealed in well known manner, this, however, being no part of the present invention. The sides 1, 2, 3, 4, respectively terminate in top closing flaps *a*, *b*, *c*, *d*, respectively,

the blank being slit to separate the said flaps from each other so that they may be 55 separately folded in the usual manner.

The flap *a* which is to be the first folded of the top closing flaps is formed with a hole 10. The flap *c* which is to be the second folded flap is formed with a hole 11 which 60 will register with the hole 10 when folded over the flap *a*. The flap *d* is slit to form an easily separable portion 30 which is intended subsequently to be completely detached from the flap to form a slide. The 65 slit instead of being continuous is interrupted at three points namely, at the two rear corners 13 and 14 and at the tip of the tongue portion 15. The stock is also cut away for a short space on both sides of the 70 tongue namely at 16 and 17 respectively, thus forming shoulders 18 and 19. In the rear part of the slide 30 there is formed a hole 20 which when the flaps are folded and the slide is closed will not register with the 75 holes 10 and 11 but which may register with said holes when the slide is drawn out.

The flap *b* is formed with a hole 21 which registers with the holes 10 and 11 when the flaps are folded. It is also formed with two 80 smaller holes 22 and 23 which when the flap *b* is folded outside of the flap *d* will expose the connecting corners 13, 14 of the slide member 30 as shown in Fig. 2. The flap *b* is also formed with an opening 24 preferably half round and of a little greater diameter than the width of the tongue portion 12 of the slide so that when the flaps are folded as in Fig. 2 the rounded front portion of the tongue will be fully exposed through the 90 opening 24 with a little marginal space around it so that the finger or small blade may be inserted to turn up the rounded end of the tongue in order to get a grasp upon it from the outside. 95

When the carton is to be set up adhesive 25 is applied to the outer face of the flap *a* with the exception of a narrow space 26 which is left unglued for the purpose to be hereinafter described. The flap *c* has adhesive applied to its outer face with the exception of a portion 27 which is left unglued extending from the outer end of the flap to some distance beyond the opening 11 of sufficient area to form an unglued 100 portion beneath the slide 30 when the flap *d* 105

is folded upon the flap *c*. The usual form of the cartons is oblong in cross section, so that the flaps *b* and *d* are longer than the flaps *a* and *c* and when the flaps *a* and *c* are folded they do not entirely overlap each other, and for this reason a narrow band 26 on flap *a* is left ungummed which will when the flap is folded form a continuation of the ungummed portion 28 on flap *d*.

10 When the carton is set up and the flaps *a*, *b*, *c*, *d*, are folded, the flap *a* will first be turned in, then the flap *c* will be folded outside of the flap *a*, the two flaps adhering together by reason of the gummed face of the flap *a* coming in contact with the under face of the flap *c*, then the flap *d* will be folded outside of the flaps *a* and *c* adhering to the flap *c* and to the exposed portion of the flap *a* which will not be entirely covered by the flap *c*, then the flap *b* is folded over upon the flap *d* and will be sealed thereto by reason of the gummed outer face of the flap *d*. When they are thus folded the holes 10, 11 and 21 will all be in registration with each other but the slide member 30 of the flap *d* which is between the flaps *c* and *b* will cover the holes 10 and 11 so that the contents of the package will be protected, the slide member being still integral with the flap by reason of its connections at 13, 14 and 15. Now, whenever, it is first desired to remove any of the contents, the connecting portions 13, 14, 15, of the slide member 30 may be cut through with a knife as shown in Fig. 3, thus leaving the part 30 free to slide. The end of the tongue 12 can be reached through the hole 24 and pulled forward to bring the slide from the position shown in Fig. 2 into the position shown in Fig. 3, the tongue being pulled through the hole 24 onto the outer face of the outer flap *b*. The shoulders 18 and 19 at the base of the tongue will if the tongue is pulled out far enough engage the shoulders 28 and 29 on the forward ends of the rectangular holes 16, 17 to limit the forward movement of the slide so that it can not be completely pulled out.

50 In practice the slide will be pulled forward sufficient only to bring the hole 20 into registration with the holes 10, 11 and 21 and thus making a clear opening through all the flaps through which the contents of the package may be shaken out by inverting the carton. After the desired quantity is removed, the slide can be pushed back to again cover the outlet holes 10 and 11 and the contents are fully protected. By this form of construction the slide does not add anything to the thickness of the cover flap when closed as it lies in the cut out space from which it was taken so that the flaps all lie flat against each other. When it is desired to again remove some of the contents, the tongue can be grasped to again pull the slide forward to open the outlet.

If it is desired to have the carton made as a sifter then instead of making a single large hole 10 in the flap *a* or a single large hole 11 in the flap *c* one or both of said flaps may be provided with a plurality of smaller holes. This will enable the contents to be sifted out in fine quantities instead of being shaken out in larger bulk. The size and number of the holes will be governed by the particular class of goods or particular use desired, that is whether desired as a sifter or to get out the goods in larger bulk.

15 The flaps *a*, *b*, *c*, *d*, have been described as the top closing flaps because that end of the carton will be the top after the package is filled and both ends are sealed, but in practice said top closing flaps will be closed and sealed before the package is filled and before the bottom closing flaps 6, 7, 8, 9, are closed and sealed. When the package is to be filled 20 the carton will be stood bottom end up so that for the time being the end which is closed by the flaps *a*, *b*, *c* and *d* will be the bottom of the carton. After the carton is filled the flaps 6, 7, 8 and 9 will be closed 25 and sealed in any suitable known manner.

25 While in describing the device, the side flap is described as being folded next to the outer flap, it is obvious that it may be folded next to the bottom flap if a tongue hole corresponding to the tongue hole 24 is formed in the two outer flaps. In such case the bottom flap should extend entirely across the end of the box, the essential features being 30 that there should be at least one flap above 100 and one flap beneath the flap out of which the slide is formed extending the full cross sectional area of the box and in that event it does not so much matter whether the extra flap is above or below the slide.

35 What I claim is:—

1. A carton having overlapping end closing flaps, one of the intermediate flaps having a cut out space surrounded on all sides by the body of the flap, a slide portion fitting into said cut out space of the flap, all of said flaps except the slide containing flap having holes which are in registration with each other, said slide normally covering the holes in all of the flaps except of the flap or flaps folded outside of it, said slide having a hole which is normally out of registration with the holes in the flaps above and below it, and which is adapted to be brought into registration with the said other holes by moving the slide, said slide being formed with a shoulder or shoulders and said slide-containing flap being formed with a shoulder or shoulders with which the shoulders on the slide are adapted to engage to limit the movement of the slide.

2. A carton having overlapping and closing flaps, one of the intermediate flaps having a slide portion fitting into a cut out por-

tion of the flap and having a forward tongue portion, all of said flaps except the slide containing flap having holes which are in registration with each other, said slide 5 normally covering the holes in all of the flaps except of the flap or flaps folded outside of it, said slide having a hole which is normally out of registration with the holes in the flaps above and below it, and which 10 is adapted to be brought into registration with the said other holes by moving the slide, the flap or flaps outside of the slide being formed with a hole over the tongue whereby the tongue may be grasped to move 15 the slide to bring the hole therein into and out of registration with the outlet holes of the other flaps, said slide being formed with a shoulder or shoulders and said slide containing flap having the cut-out opening for 20 the slide formed with a shoulder or shoul-

ders which serve to limit the movement of the slide.

3. A carton having overlapping end closing flaps, the flap which is intermediate the other flaps having a partially cut out portion with narrow connecting portions uniting it with its flap and adapted to be detached by severing said connecting portions to form a slide, the flap or flaps outside of 25 said intermediate flap having a hole exposing one end of said slide portion, and having holes exposing the said connecting portions between the slide portion and the flap.

In testimony whereof I affix my signature, 30
in presence of two witnesses.
